UNITED STATES PATENT OFFICE.

GEORGE HOLLIS MEGLOUGHLIN, CHARLES AUDLEY BELFORD, AND EDWARD ROBERT BRENNER, OF OTTAWA, CANADA.

CARDBOARD BOX.

SPECIFICATION forming part of Letters Patent No. 687,643, dated November 26, 1901.

Application filed November 2, 1900. Serial No. 35,303. (No model.)

To all whom it may concern:

Be it known that we, GEORGE HOLLIS MEGLOUGHLIN, manager, CHARLES AUDLEY BELFORD, salesman, and EDWARD ROBERT BRENNER, clerk, subjects of the Queen of Great Britain, residing in the city of Ottawa, in the county of Carleton, in the Province of Ontario, Canada, have invented new and useful Improvements in Cardboard Boxes, of which

10 the following is a specification.

Our invention relates to improvements in cardboard boxes; and the object of the invention is to construct a box the height of the walls of which may be adapted to the 15 quantity of the goods contained therein; and it consists, essentially, of a cardboard box having perforated or scored incisions formed in the walls thereof circumferentially arranged in tiers corresponding in number to 20 the goods contained in the box and having strips of paper or other suitable material arranged inside the walls to close such perforations.

Figure 1 is a general perspective view of 25 our box. Fig. 2 is a cross-section through Fig. 1. Fig. 3 is an enlarged detail of a portion of the box.

In the drawings like letters of reference indicate corresponding parts in each figure.

30 A is our box, formed of walls a, bottom a', and lid a².

B represents longitudinal perforations formed in the walls arranged endwise and separated by thin dividing portions B'.

35 C represents strips of tissue-paper or other suitable material secured to the inside of the walls of the box above each row of perforations, so as to overlap same. These are provided so as to prevent any dust penetrating to 40 the interior of the box, and thus spoiling the goods contained therein.

When one or more articles are permanently removed from the box, one or more portions of the box may be removed, thus proportionately reducing the height of the wall, so as to bring 45 it to the level of the goods remaining in the box. This is of great importance, as salesmen frequently wish to know how many articles are contained in the boxes without removing the same from the shelves. By the 50 use of our box stock can be readily taken at almost a glance. In the use of the old box each one had to be removed from the shelf and the cover taken off before the quantity 55 of goods contained therein is shown. By our box this is obviated. For the above reasons many articles which would otherwise be put up in boxes are placed in paper wrappings. This occasions a great loss of time and is 60 very inconvenient.

By the use of our box goods may be arranged neatly in a minimum amount of space and with a great economy of time.

What we claim as our invention is—

As an improved article of manufacture, a 65 box made of card or other suitable material having the sides thereof formed with perforated lines around the box dividing said sides into detachable sections, and labels affixed to the inside of the box over said perforated lines as and for the purpose specified.

70 Signed at the city of Ottawa this 15th day of October, 1900.

GEORGE HOLLIS MEGLOUGHLIN.
CHARLES AUDLEY BELFORD.
EDWARD ROBERT BRENNER.
